CENTRIFUGE BOWL DRIVE INCORPORATING A PAIR OF CLUTCHES

Filed Oct. 16, 1944

FIG. 1.

UNITED STATES PATENT OFFICE

2,476,377

CENTRIFUGE BOWL DRIVE INCORPORATING A PAIR OF CLUTCHES

Camille Clare Sprankling Le Clair, Acton, London, England, assignor to Tecalemit Limited, Brentford, England, a corporation of Great Britain

Application October 16, 1944, Serial No. 558,881
In Great Britain November 29, 1943

8 Claims. (Cl. 233—23)

1

This invention relates to centrifuge machines, particularly those used for the removal of suspended matter from liquids such as oils. More particularly, this invention relates to an improved drive for the bowl of such centrifuge machines.

A particular object of this invention is to provide improved centrifuge machines for cleansing lubricating oil used in internal combustion engines, more especially those of aircraft and automobiles.

In such applications of centrifuge machines the space available for a centrifuge machine is usually severely limited. This necessitates the use of a relatively small centrifuging bowl, so that in order that it may perform its functions properly it is necessary that the bowl shall run at an extremely high speed, at which speeds, quick acceleration and deceleration become impossible.

In the application of the invention to internal combustion engines, it will usually not be feasible to drive the machine by means of a separate motor and a drive has to be taken from the main engine. Such a drive, however, not only varies over a wide range of speed but also frequently accelerates and decelerates quickly, far quicker than the high speed bowl of the centrifuge can possibly follow, so that a fixed speed ratio cannot be maintained. Hence, another object of the invention is to provide an elastic coupling between the drive and the centrifuging bowl which will permit of a change of speed ratio taking place.

According to the present invention, a centrifuge machine comprising a hollow centrifuge bowl in which liquids and oils are cleansed by centrifugal action, is characterised by the feature that the bowl is rotated through clutch means which allows the driving means to overrun the bowl when the speed of the said means is accelerating, and also through other clutch means which allows the bowl to overrun its driving means when the speed of the latter is decelerating or has stopped. Thus, the bowl may be driven by a driving means through a safety or slipping friction clutch, which allows the bowl to lag behind and thus gradually to acquire its designed speed when the speed of said driving means is accelerating, and also through a free-wheel clutch, which allows the bowl to overrun its driving means when the speed of the latter is decelerating or has stopped.

Various types of safety or slipping clutches may be used but in the specific construction described hereinafter, the clutch is of the plate disc type, in which discs of fibre, fabric or other frictional

2

material are resiliently pressed into contact with a flange on the driven bowl-supporting spindle and also into contact with upper and lower metal plates forming parts of the clutch. In the same construction, the centrifuge bowl is driven through gearing including a primary or first drive gear wheel, which is driven from the top (i. e., driven) friction clutch-plate through a free-wheel clutch. In this instance, the latter is of the type including a number of rollers which are lodged in spaced tapered housings formed in a boss on the said top driven clutch plate and are wedged between the bottoms of said housings and the wall of a circular recess formed in a hollow boss on said first drive gear wheel surrounding the boss on the said top, driven, clutch plate.

It is also preferred to feed the liquid to be cleansed through the interior of a hollow centrifuge bowl supporting spindle upon which the bowl is turnably arranged, the bowl being driven at a much greater speed than said driving means through a train of gearing connecting the said first drive gear wheel to the bowl.

Further constructional features of the invention will be described hereinafter.

One constructional form of the invention, applied to a centrifuging machine for use in the cleansing of the lubricating oil of an aircraft engine, is shown by way of example, on the accompanying sheet of drawings, whereon:

Fig. 1 is a sectional elevation of the machine; and

Fig. 2 is a sectional plan view of the free wheel drive between the safety or slipping clutch and the centrifuge bowl spindle.

Referring to the drawings:

The machine comprises a housing 1 closed by a top cover 2, and provided with a clean oil outlet 3. The centrifuge bowl 4 is driven from the engine camshaft (not shown) through a hollow driving shaft 5, the bottom end of which is provided with a gear wheel 6 adapted to mesh with a pinion on the camshaft. The upper end of the hollow driving shaft is turnable in a bearing 7 arranged in the bottom closure 8 of the housing, the said end fitting into, and being operatively connected to, the bottom end of the centrifuge bowl supporting spindle 9 which is coaxial with the driving shaft and is hollow from its bottom end to a position short of its top end where it is turnably arranged in a bearing 10 provided in the cover 2 of the housing. An oil supply pipe 11 connected to the engine oil pump (not shown) is fitted in a hole in the pinion 6 at the bottom end 55 of the hollow driving shaft 5 and thus serves to

feed oil through the latter into the bowl supporting spindle 9, from which latter the oil can flow into the bowl through a number of ports 12 formed in the spindle.

At a distance above the flange 13 of the bearing 7, in which the adjacent ends of the hollow driving shaft and centrifuge bowl supporting spindle are turnably arranged, the spindle is formed or provided with a flange 14 which acts as the driving member of a safety friction clutch of the plate or disc type. This clutch also comprises two discs 15 and 16 of fibre, fabric or like frictional material arranged on the said spindle above and below the driving flange. Below the bottom fibre or fabric disc there is a metal bottom clutch plate 17 (hereinafter referred to as a "loose clutch plate") which is slidably arranged on the said spindle and which runs on the flange 13 of the bearing 7. A metal top clutch plate 18 (hereinafter referred to as a "fixed clutch plate") is also arranged on the spindle 9 above the top fibre or fabric disc 15, this clutch plate serving to carry a number of spaced, downwardly-depending pins 19 which project through holes 20 formed in the loose clutch plate 17. A coil spring 21 is arranged upon the part of each of the pins 19 which projects through the bottom clutch plate, the bottom end of each spring being supported by a washer 22 held on to the pin by a nut 23 screwed on to the latter. Thus, by tightening or slackening the nuts 23, the pressure exerted on the two fibre or fabric discs 15 and 16 between the fixed and loose clutch plates 18 and 17 and the driving flange 14 can be adjusted. The clutch plates 18 and 17 will normally rotate at the speed of the driving shaft 5, but in the event of the resistance to rotation exceeding a predetermined torque the clutch will slip. The amount of torque to cause such slipping can be adjusted by means of the nuts 23 as mentioned above.

A circular boss 24 formed on the top face of the fixed clutch plate 18 projects upwards into, and is turnable within, a circular recess 25 formed in a boss 26 projecting downwards from the bottom of a first drive gear wheel 27, which is rotatably mounted upon the centrifuge bowl supporting spindle 9 above the fixed clutch plate 18. The said boss 26 projects downwards through a hole formed centrally in a plate member 28 encircling the said spindle fitted and fixed non-rotatably in a recess 29 formed in the housing just above the fixed clutch plate. A number of spaced, tapered notches 30, see Fig. 2, is formed in the periphery of the boss 24 on the top clutch plate, and in each of these notches there is a vertically-arranged roller 31 which is normally forced towards the shallower end of said notch by a coil spring 32, whereby the roller is normally wedged between the bottom of the notch and the wall of the recess 25 in the boss 24 on the said first drive gear wheel 27. This arrangement provides a free-wheel clutch, whereby the gear wheel 27 is normally driven positively in the same direction, and at the same speed, as the centrifuge bowl supporting spindle 9 but which permits the gear wheel 27 to overrun the supporting spindle.

The first drive gear wheel 27 meshes with a number of pinions 33 turnably mounted upon spaced spindles 34 fixed to, and projecting upwards from, the said fixed plate member 28. Each of the pinions is integral with, or attached to, a gear wheel 35 and these gear wheels mesh with a pinion 36 which is formed on a sleeve 37 turnably arranged upon the centrifuge bowl supporting spindle 9 above the first drive gear wheel 27.

At its top end the sleeve 37 is formed with a flange 38 which is attached to the bottom wall of the hollow centrifuge bowl.

The centrifuge bowl used in this machine may be said to resemble two superimposed, hollow truncated cones 39 and 40 having their adjacent ends of larger diameter connected by the curved central part 41 of the bowl. The top of the bowl is formed with a large opening 42 and the bottom is formed by the said bottom wall to which the flange 38 on the sleeve 37 is attached. The ports 12 in the centrifuge bowl supporting spindle 9 provide communication between the interior of the latter and the interior of the bowl.

In operation, oil to be cleansed is forced axially upwards through the interiors of the hollow driving shaft 5 and centrifuge bowl supporting spindle 9, whence it flows through the ports 12 into the bowl 4 where it is centrifuged until it spills over the edge of the opening 42 in the top of the bowl and is caught in the casing 1 whence it drains away through the clean oil outlet 3. Suspended matter is retained in the bowl, from which it can be scooped out by a curved sludge removal pipe 43 arranged in the casing. This pipe is adapted to be pivoted about one end 44 and whereas its opposite end is normally arranged outside the centrifuge bowl, that end, as shown in broken lines, can be swung downwards into the bowl through the hole 42 when it is required to remove any sludge that has collected.

The speed at which the bowl runs can be arranged to suit operating conditions, different oils and so on by suitably adjusting the ratio of the gears referred to above. In the case of the machine now being described, the gear ratio is such that the bowl 4 rotates at about four times the speed of the centrifuge bowl supporting spindle 9. When the engine is started, its acceleration is

far greater than the centrifuge bowl can follow and, consequently, the said safety friction clutch will slip, the driving flange 14 on the centrifuge bowl supporting spindle 9 slipping relatively to the two fibre or fabric discs 15 and 16. As the speed of the bowl increases to the designed operating speed, the slipping of the clutch decreases until eventually there is no slipping. When the engine decelerates, the energy of the bowl is not dissipated by overcoming friction in the clutch, but the bowl is permitted to continue running at or near its full speed for some time by over-running the free-wheel clutch.

In a modification the free wheel clutch (or clutches) may be incorporated within some other member of the gear train such as the pinions 33, gearwheels 35, or the final pinion 36.

I claim:

1. In a centrifuge machine comprising a hollow centrifuge bowl in which liquids and oils are cleansed by centrifugal action of matter suspended therein, means for driving the bowl comprising a driving member, a driven member attached to the bowl and rotatable relative to said driving member, first clutch means comprising a slipping friction clutch operatively associated with said driving member, and second clutch means comprising a free wheel clutch operatively associated with said first clutch means and with said driven member, said first clutch means being adapted to allow said driving member to overrun said driven member when the driving member is accelerating, and said second clutch means being adapted to allow said driven member to overrun the driving member when the latter is decelerating or has stopped, and a spindle connected

to said driving means and rotatable relative to said bowl, said slipping friction clutch comprising a metal driving plate in fixed relation on said spindle, a pair of discs of frictional material each engaging a face of said plate, biasing means urging said discs and plates into frictional driving engagement, and adjusting means to vary the pressure of said biasing means for controlling the torque transmittable by said clutch without relative slipping between said plate and discs.

2. In a centrifuge machine comprising a hollow centrifuge bowl in which liquids and oils are cleansed by centrifugal action of matter suspended therein, means for driving the bowl comprising a driving member, a driven member attached to the bowl and rotatable relative to said driving member, first clutch means comprising a slipping friction clutch operatively associated with said driving member, and second clutch means comprising a free wheel clutch operatively associated with said first clutch means and with said driven member, said first clutch means being adapted to allow said driving member to overrun said driven member when the driving member is accelerating, and said second clutch means being adapted to allow said driven member to overrun the driving member when the latter is decelerating or has stopped, and a spindle connected to said driving means and rotatable relative to said bowl, said slipping friction clutch comprising a metal driving plate in fixed relation on said spindle, a pair of discs of frictional material each engaging a face of said plate, a fixed clutch plate and a loose clutch plate each rotatably mounted on said spindle, said loose clutch plate having a plurality of apertures therein, a plurality of pins on said fixed plate each projecting through an aperture in said loose plate, said driving plate and said discs being disposed between said fixed and loose clutch plates, a plurality of springs pressing on said loose clutch plate to urge said driving plate, discs and fixed plate into frictional driving engagement, each of said springs being mounted on one of said pins, and a nut screwed on each pin for adjusting the pressure of the spring mounted on said pin.

3. In a centrifuge machine comprising a hollow centrifuge bowl in which liquids and oils are cleansed by centrifugal action of matter suspended therein, means for driving the bowl comprising a driving member, a driven member attached to the bowl and rotatable relative to said driving member, first clutch means comprising a slipping friction clutch operatively associated with said driving member, second clutch means comprising a free wheel clutch operatively associated with said first clutch means and with said driven member, said first clutch means being adapted to allow said driving member to overrun said driven member when the driving member is accelerating, and said second clutch means being adapted to allow said driven member to overrun the driving member when the latter is decelerating or has stopped, a spindle connected to said driving means and rotatable relative to said bowl, and a gear train operatively connecting said driving means to said bowl for rotation of said bowl at a different speed than said spindle, said gear train including a primary drive gear wheel, a plurality of secondary gear wheels, a plurality of pinions engaging said primary drive gear wheel mounted on fixed spaced supports and in fixed relation to said secondary gear wheels, and a final drive pinion connected to said bowl, each of said

secondary gear wheels engaging with said final drive pinion.

4. In a centrifuge machine comprising a hollow centrifuge bowl in which liquids and oils are cleansed by centrifugal action of matter suspended therein, means for driving the bowl comprising a driving member, a driven member attached to the bowl and rotatable relative to said driving member, first clutch means comprising a slipping friction clutch operatively associated with said driving member, second clutch means comprising a free wheel clutch operatively associated with said first clutch means and with said driven member, said first clutch means being adapted to allow said driving member to overrun said driven member when the driving member is accelerating, and said second clutch means being adapted to allow said driven member to overrun the driving member when the latter is decelerating or has stopped, a hollow spindle connected to said driving means and rotatable relative to said bowl, and a port in said spindle providing communication between the interior thereof and said bowl for feeding liquid or oil into the bowl through said spindle.

5. A centrifuge machine comprising in combination a housing; an outlet from said housing for centrifuged liquid; a centrifuge bowl mounted within said housing and having a double conical shape, said centrifuge bowl having an opening at the upper side thereof of less diameter than the diameter of the bowl at its widest point; means for driving said centrifuge bowl comprising a driving member, a driven member attached to said bowl and rotatable relative to said driving member, first clutch means operably associated with said driving member, and second clutch means operatively associated with said first clutch means and with said driven member, said first clutch means being adapted to allow said driving member to overrun said driven member when the driving member is accelerated, and said second clutch means being adapted to allow said driven member to overrun said driving member when the latter is decelerated or has stopped; said driving member comprising in part a hollow spindle through which the liquid to be centrifuged enters said bowl; said spindle having ports communicating with said centrifuge bowl; and means for removing the sludge from said centrifuge bowl.

6. A centrifuge machine comprising in combination a housing; an outlet from said housing for centrifuged liquid; a centrifuge bowl mounted within said housing, said centrifuge bowl having an opening at the upper side thereof of less diameter than the diameter of the bowl at its widest point; means for driving said centrifuge bowl comprising a driving member, a driven member attached to said bowl and rotatable relative to said driving member, first clutch means operably associated with said driving member, and second clutch means operatively associated with said first clutch means and with said driven member, said first clutch means being adapted to allow said driving member to overrun said driven member when the driving member is accelerated, and said second clutch means being adapted to allow said driven member to overrun said driving member when the latter is decelerated or has stopped; said driving member comprising in part a hollow spindle through which the liquid to be centrifuged enters said bowl; and said spindle having ports communicating with said centrifuge bowl.

7. A centrifuge machine comprising in combination a housing; an outlet from said housing

for centrifuged liquid; a centrifuge bowl mounted within said housing, said centrifuge bowl having an opening at the upper side thereof of less diameter than the diameter of the bowl at its widest point; means for driving said centrifuge bowl comprising a driving member, a driven member attached to said bowl and rotatable relative to said driving member, first clutch means operably associated with said driving member, and second clutch means operatively associated with said first clutch means and with said driven member, said first clutch means being adapted to allow said driving member to overrun said driven member when the driving member is accelerated, and said second clutch means being adapted to allow said driven member to overrun said driving member when the latter is decelerated or has stopped; said driving member comprising in part a hollow spindle through which the liquid to be centrifuged enters said bowl; said spindle having ports communicating with said centrifuge bowl; and means for removing the sludge from said centrifuge bowl, said last mentioned means comprising a pipe which enters said bowl through said opening.

8. A centrifuge machine comprising in combination a housing; an outlet from said housing for centrifuged liquid; a centrifuge bowl mounted within said housing, said centrifuge bowl having an opening at the upper side thereof of less diameter than the diameter of the bowl at its widest point; means for driving said centrifuge bowl comprising a driving member, a driven member attached to said bowl and rotatable relative to said driving member, first clutch means operably associated with said driving member, and second clutch means operatively associated with said

5 first clutch means and with said driven member, said first clutch means being adapted to allow said driving member to overrun said driven member when the driving member is accelerated, and said second clutch means being adapted to allow said driven member to overrun said driving member when the latter is decelerated or has stopped; said driving member comprising in part a hollow spindle through which the liquid to be centrifuged 10 enters said bowl; said spindle having ports communicating with said centrifuge bowl; and means for removing the sludge from said centrifuge bowl, said last mentioned means comprising a pipe adapted to be entered into said bowl through said opening and which is pivotally mounted within said housing so that its position relative to said bowl may be adjusted.
